TOY

Florence Krempler, Stapleton, Staten Island, N. Y.

Application October 17, 1939, Serial No. 299,857

1 Claim. (Cl. 272—52)

This invention relates to toys. It is particularly directed to a bouncing toy such as a spring chair, or a pony ride for tots or children.

An object of this invention is to provide a toy of the character described, on which a tot or child will be able to ride in comfort and safety, protected from all harm and danger.

Another object of this invention is to provide a strong, rugged and durable spring bouncing toy of the character described, in the shape of a spring chair on which a tot may sit and either rest or bounce up and down by pumping with his feet on the floor, which will require very little effort, the springs of the chair being enclosed all around with an expandable material, for appearance and safety.

Yet another object of this invention is to provide a toy of the character described, consisting of a bouncing spring chair fixed to a platform, on which is mounted a stationary pony simulating member, disposed in front of the spring chair and provided with reins which may be held by the child sitting on the spring chair, the pony simulating member being further provided with footrests on which the child may place his feet, whereby the child can bounce up and down while sitting on the chair, either by pumping with his feet on the floor or by putting his feet on the footrests. Another method of using this toy, is for the child to pump while his feet are on the floor, and when the device gets into motion, to transfer his feet to the side footrests, and keep going; or he can sit in the chair with his feet on the footrests and enjoy a mild ride, which the weight of his body and the vibration of the springs will permit.

Yet another object of this invention is to provide an improved toy of the character described, which shall be relatively inexpensive to manufacture, amusing and healthful to use, and which shall yet be practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which are shown various possible illustrative embodiments of this invention,

Fig. 1 is an elevational, cross-sectional view 55

of a spring chair for tots, embodying the invention:

Fig. 2 is a rear, elevational view thereof;

Fig. 3 is a top plan view thereof;

Fig. 4 is a cross-sectional view taken on line 4—4 of Fig. 1;

Fig. 5 is a rear, elevational view of the spring chair shown in Fig. 1, with the backrest, partly cut out;

Fig. 6 is a side, elevational view of a pony ride for tots, embodying the invention, with parts in cross-section;

Fig. 7 is a top plan view of the toy shown in Fig. 6; and

Fig. 8 is a cross-sectional view taken on line 8—8 of Fig. 6, with part of the accordion pleated cover removed.

Referring now in detail to the drawings, and particularly to Figs. 1 to 5, 10 designates a spring chair for tots embodying the invention. The same comprises a substantially square base 11 formed with four circular recesses 12 in the top surface thereof. Mounted on the base 11 are four similar conical springs 13, the lower ends whereof are received within the recesses 12. The springs 13 decrease in diameter toward the top. Mounted on the upper end of each spring, is a flat circular metal cap 14, having an annular downwardly extending flange 15.

Supported on the springs 13, and contacting the caps 14, is a seat 16. The caps 14 may be screwed to the underside of the seat 16, by screws 17, passing through the central openings in the caps. Attached to the rear edge 18 of the seat 16, is a backrest 19, preferably formed with a hand slot 20 to facilitate lifting the spring chair.

The lower ends of the spring 13 may be attached to the base 11 in any suitable manner. The upper ends of spring 13 are likewise preferably fixed to the caps 14 in any suitable manner. Attached to the seat 16 and backrest 19 and interconnecting the same, are angle shaped armrests 24, as shown in Fig. 1 of the drawings.

The springs 13 are preferably hidden from view, being covered by an accordion pleated cover 25, having front, side and rear walls, and attached at its upper and lower ends to the seat 16 and base 11, respectively, by nails 16a and 11a.

The manner of using the spring chair will now be described:

A child may sit in the chair and bounce up and down. The child can either ride up and down in the chair or rest in the chair. It may be made in several sizes to suit boys and girls of various ages. Children have a desire to bounce

up and down, and this toy will take the children away from bouncing on the more expensive davenport or other cushioned chairs. The child may pump himself up and down with his feet on the floor while expending very little energy.

Referring now to Figs. 6 to 8, inclusive, 10a designates a pony ride for tots. The same comprises a flat platform or baseboard 30. Attached to the front edge of the baseboard 30, is a vertical wall 31, which rises somewhat above the baseboard. Also attached to the side edges of the board, are parallel, vertical walls 32, extending about half the length of the board and to the same height as the wall 31. Attached to the rear edge of the board 30, is a vertical wall 33, the upper edge of which is at the level of the upper edge of wall 31. Also attached to the side edges of the board 30, are walls 35 extending forwardly from the rear wall 33. Said walls constitute guard rails for the front and rear ends of the platform.

It will be noted that the adjacent edges of the walls 32 and 35 are spaced from one another, to permit the child to step upon or enter the platform or baseboard 30 between the guard rails.

Mounted on the rear of the platform and between the walls 35, is a spring chair 10, such as disclosed in Figs. 1 to 5. The base 11 of the spring chair 10 may be bolted or otherwise attached to the baseboard, as shown at 36.

Mounted on the central part of the baseboard 30, and extending upwardly therefrom, is a short post or pin 37. Supported on said pin and on the baseboard is an upstanding, longitudinal, vertical, flat board or member 38, having the shape of the front part of a running pony. The post or pin 37 supports the rear end of the board 38, and the portion 40 of said board, simulating the front legs of the pony, contacts the baseboard and is fixed thereto in any suitable manner. Attached to the head simulating portion 40a, are a pair of reins 41 which may be held by a child sitting on the spring chair 10. There is also mounted at the upper, rear edge of member 38, a pair of handle bars 42 which may be grasped by said child. Mounted at the lower rear edge of board 38, are a pair of outwardly extending footrests 44, on which the child may place his feet.

This pony ride will be a great delight to the young child and he will be able to ride in comfort, safely protected from all harm and danger, and without requirement for anyone lifting him whenever he wishes to ride the pony. This device will enable the child to ride without using too much energy, and holding the reins while riding, will give the child a thrill.

It will be noted that the pony is stationary, firmly supported on the post or pin 37, with one hoof of the pony also fastened to the baseboard to make it secure. The seat moves up and down

on four large springs beneath it according to the degree of pumping. The child can pump with his feet flat on the floor or he can put them on the side footrests 44. The child may also pump while his feet are on the floor, and when the device gets in motion transfer his feet to the side footrests and keep going; he can sit in the seat 10 with his feet on the rests and enjoy a mild ride which the weight of his body and the vibration of the springs will permit. The child may rest on the spring chair 10 or he can ride the toy more energetically, like a jockey.

The board 39 is preferably painted to resemble a pony on both sides. The board 39 may, of course, be replaced by a pony simulating member of full thickness. The four springs 13 are attached to the bottom or base of the chair, one in each corner, and are smaller at the top than at the bottom, the widest part being at the bottom for proper balance and smooth working.

The springs should not be too sturdy and not too loose, but firm enough to go up and down under the weight of a small tot. When the child is merely sitting in the seat, it should go down a little way under his weight. When the child is not sitting in the chair 10, the height of the seat is substantially at the level of the top of the pony's body.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

A toy comprising a platform, an upstanding member on said platform, a spring chair on the platform in back of the upstanding member and spaced therefrom, a flexible element on said upstanding member adapted to be held by a child sitting on the spring chair, footrests on the upstanding member for the feet of the child sitting on the spring chair, said spring chair comprising a base fixed to the platform, a plurality of conical springs on said base, a seat on said springs, a backrest fixed to said seat and extending upwardly therefrom, guard rails at the front and rear of the platform, and said guard rails being spaced from each other at each side of the platform, the space between the guard rails coinciding with the space between the upstanding member and the spring chair, to permit the child to enter upon the platform between said guard rails.

FLORENCE KREMLER.
